WILLIAM LINDSAY, OF TORONTO, ONTARIO, CANADA, ASSIGNOR TO MANTON BROTHERS, OF TORONTO, CANADA

INK AGITATOR FOR PRINTING PRESSES

Application filed March 6, 1929. Serial No. 344,815.

My invention relates to an ink agitator for printing presses as described in this specification and illustrated by the accompanying drawings and being the most acceptable form 5 of my invention.

An object of my invention is to build an agitator wherein the travel or stroke of the agitating finger is adjustable and can be made to travel within any portion of the 10 fountain; another object is to so design the device that one or more fingers can be used; another object is to provide very simple and efficient driving means; and generally, to improve on existing ink agitators.

15 In the drawings:

Figure 1 is a fragmentary front view of an agitator constructed in accordance with my invention;

Figure 2 is a side elevation of the finger 20 carriage with guard;

Figure 3 is a front elevation of the finger carriage frame;

Figure 4 is a view in section showing the clutch locking plunger;

25 Figure 5 is a fragmentary side elevation of a typical printing press showing the method of supporting the rack from and in front of the ink fountain;

Figure 6 is a fragmentary side elevation 30 showing method of actuating the drive shaft from the printing bed drive;

Figure 7 is a perspective view of the bracket mounting one end of the drive shaft;

Figure 8 is a side elevation of the bracket 35 in which pivots the drive shaft bearing;

Figure 9 is a front elevation of one of the stationary bevel gears;

Figure 10 is a fragmentary top plan view 40 showing method of driving the drive shaft from the printing bed drive;

Figure 11 shows method of mounting two or more agitating fingers.

Like numerals of reference indicate corresponding parts in the various figures.

45 Referring to the drawings, 10 designates the ink fountain and 11, the fountain roller of a typical printing press shown in parts only and designated by the numeral 12.

The ink agitating finger 13, of conventional design, is hinged to a bracket 14 secured

to the frame 24 of a carrier 15; the carrier is formed to slide on a rack 16 positioned adjacent the fountain and in parallel arrangement with the fountain and roller, and secured to the press (see Figure 5) as with 55 brackets 17. As will be seen, the rack is disposed so that its teeth face downwardly.

In the carrier is journalled a transverse shaft 19, on which are fixed a gear or pinion 18 meshing with the rack and a worm gear 60 20. As the worm gear 20 is fixed on the shaft and the gear 18, also fixed on the same shaft, meshes with the rack, it follows that the carrier can be shifted or moved on the rack in opposite directions according to direction 65 of rotation of the worm gear.

A shaft 22 is journalled in the brackets 17, adjacent the rack and in parallel arrangement therewith. Turning with this shaft 22 but free to slide or move axially thereupon, 70 is a worm 21 the function of which is to rotate the worm gear 20 from the rotation of the shaft 22, so that the carrier can be moved back and forth on the rack according to the direction of rotation of the shaft. The worm 75 21 is kept in meshing engagement with the worm gear 20 by providing an open space 23 (see Figure 3) in the frame 24 of the carrier, so that the worm travels with the carrier while always remaining in mesh with the 80 worm gear 20. A guard or gear box 25 is preferably provided as shown in Figure 2.

One end of the shaft 22 projects beyond one of the bearings 17 and is supported from the rack as with hangers 26. Free to turn on the 85 shaft 22 are two bevel gears 27 and 27A formed with clutch teeth 33A and extensions or sleeves 33B, these gears being disposed on the shaft between the hangers 26 and with their clutch teeth facing as shown (see Figure 1); on the sleeves 33B of the bevel gears is journalled a bracket 31 which extends rearwardly to provide a bearing for one end of the drive shaft 30 and is formed at the forward portion to receive spring-actuated 90 plungers 29.

As the bracket 31 must be secured in a fixed relation with respect to the hangers 26, I provide removable collars 33 on the sleeves 100

of the bevel gears, thus also rotatably securing the gears in the bracket.

Fixed on the shaft 22, between the bevel gears 27 and 27A, is a clutch member 28 having clutch teeth formed to engage with the clutch teeth 33A of the gears and having a centre disc-like tapered portion adapted to be slidably engaged by the tapered plungers 29. The function of the plungers is to retain the clutch member in mesh or engagement with either gear until sufficient axial pressure on the shaft causes the plungers to be actuated outwardly and the clutch member to leave the gear and be thrown into mesh with the other gear. For instance referring to Figure 1 wherein the clutch is shown as engaging with the gear 27A, the plungers releasably lock and retain the clutch in that position until the plungers are forced outwardly to allow the clutch to leave the gear 27A and mesh with the other gear 27.

Fixed on the drive shaft 30 is a bevel gear 29A meshing with both of the gears 27 and 27A and rotating both of these gears together but in opposite directions. It follows therefore that the direction of rotation of the shaft 22 changes as the clutch member disengages from one gear and engages with the other.

To shift the clutch member, and more particularly to shift the shaft 22 axially, I provide two collars 47 adjustably secured on the shaft, and springs 49, and loose collars 50. Upon the engagement of the carrier with one of the collars 50, the corresponding spring 49 begins to be compressed, and when enough resiliency is stored in the spring to force the plungers 29 outwardly, the shaft shifts until the clutch member engages with the bevel gear toward which it is shifted. The length of travel of the agitating finger is increased or decreased by spacing the collars 47 farther or nearer apart, respectively. It follows also that the agitating finger can be made to travel within any portion of the fountain, the portion travelled corresponding to the distance between and location of the collars 47.

Where more than one finger is to be used, I provide an extension member 48 removably secured to the bracket 14 as with suitable screws 49A, the extension being provided with a shoe 49C sliding on the rack, the extension is provided with a plurality of holes 53 or slots 49B for removably and adjustably mounting the bracket 14A having the finger 13A; as many brackets 14A may be used as there are holes in the extension. Similarly, a second extension 48A may be used where required.

The drive shaft 30 may be driven from the printing bed drive 37 in the following manner:

A gear 38 is fixed on a shaft 39 journalled in a bearing 39A secured to the press and

meshing with the drive 37; on the shaft 39 is fixed a spiral gear 40 positioned to be engaged by a co-acting spiral gear 40A fixed on the shaft 30 which has the universal joint 41 to make same flexible; the spiral 40 is engaged by the spiral 40A and disengaged therefrom by providing a bearing 42 pivoted in a bearing 43 having a plunger 44 friction-held in a hole 45 in the bracket 39A.

What I claim is:

1. In an ink agitator for printing presses, a rack mounted adjacent the ink fountain in parallel arrangement therewith, a finger carrier slidably mounted on said rack and having a gear meshing with said rack, a shaft journalled adjacent said rack in parallel arrangement therewith and operating to rotate in alternate directions successively and means for actuating said gear from the rotation of said shaft.

2. In an ink agitator for printing presses, a rack mounted adjacent the ink fountain in parallel arrangement therewith, a finger carrier slidably mounted on said rack and having a gear meshing with said rack, a shaft journalled adjacent said rack in parallel arrangement therewith and operating to rotate in alternate directions successively, means actuating said gear from the rotation of said shaft, and means for reversing the rotation of said shaft at determinable lineal travel intervals of said carrier.

3. In an ink agitator for printing presses, a rack mounted adjacent the ink fountain in parallel arrangement therewith, a finger carrier slidably mounted on said rack and having a gear meshing with said rack, a shaft journalled adjacent said rack, in parallel arrangement therewith and operating to rotate in alternate directions successively, means for actuating said gear from the rotation of said shaft, and carrier-operated means for reversing the rotation of said shaft at determinable lineal travel intervals of said carrier.

4. In an ink agitator for printing presses, a rack mounted adjacent the ink fountain in parallel arrangement therewith, a finger carrier slidably mounted on said rack a gear journalled in said carrier and meshing with said rack, a shaft journalled adjacent said rack in parallel arrangement therewith and movable axially between determined limits, means operating to drive said shaft in opposite directions alternately upon the axial shifting thereof, means driving said gear from the rotation of said shaft, and resilient means adjustable on said shaft co-acting with said carrier in shifting said shaft axially at determinable lineal travel intervals of said carrier.

5. In an ink agitator for printing presses, a rack mounted adjacent the ink fountain in parallel arrangement therewith, a finger carrier slidably mounted on said rack and having

- a gear meshing with said rack, a shaft journaled adjacent said rack and movable axially to a limited extent, means for actuating said gear from the rotation of said shaft, a pair of continuously-driven gears rotating in opposite directions on said shaft and having clutch teeth, a clutch member fixed on said shaft between said last-mentioned gears and spring-held in clutch with either of said 5 gears, and means on said shaft co-acting with said carrier in shifting said shaft axially in alternate directions successively. 6. In an ink agitator for printing presses, a rack mounted adjacent the ink fountain in parallel arrangement therewith, a finger carrier slidably mounted on said rack and having a gear meshing with said rack, a shaft journaled adjacent said rack and movable axially to a limited extent, means for actuating 10 said gear from the rotation of said shaft, a pair of continuously-driven gears rotating in opposite directions on said shaft and having clutch teeth, a clutch member fixed on said shaft between said last-mentioned gears and spring-held in clutch with either of said 15 bevel gears, and resilient means adjustably secured on said last-mentioned shaft co-acting with said carrier in shifting said shaft axially. 7. In an ink agitator for printing presses, a rack mounted adjacent the ink fountain in parallel arrangement therewith, a finger carrier slidably mounted on said rack and having a gear meshing with said rack, a shaft journaled adjacent said rack and movable axially to a limited extent, means for actuating 20 said gear from the rotation of said shaft, a pair of continuously-driven gears rotating in opposite directions on said shaft and having clutch teeth, a clutch member fixed on said shaft between said last-mentioned gears and spring-held in clutch with either of said 25 gears, and means adjustable on said shaft co-acting with said carrier in shifting said shaft axially in alternate directions successively at determinable lineal 30 travel intervals of said carriage. 8. In an ink agitator for printing presses, a rack mounted adjacent the ink fountain in parallel arrangement therewith, a finger carrier slidably mounted on said rack and having a gear meshing with said rack, a shaft journaled adjacent said rack and movable axially to a limited extent, means for actuating 35 said gear from the rotation of said shaft, a pair of continuously-driven gears rotating in opposite directions on said shaft and having clutch teeth, a clutch member fixed on said shaft between said last-mentioned gears, a spring-operated plunger co-acting with said clutch member in releasably locking same 40 in clutch with either of said last-mentioned gears, and means adjustable on said shaft co-acting with said carrier in shifting said shaft axially in alternate directions successively at determinable lineal 45 travel intervals of said carriage. 9. In an ink agitator for printing presses, a rack mounted adjacent the ink fountain in parallel arrangement therewith, a finger carrier slidably mounted on said rack, a transverse shaft journaled in said carrier, a gear fixed on said shaft meshing with said rack, a worm gear fixed on said shaft, a shaft journaled adjacent said rack in parallel arrangement 50 therewith and operating to rotate in alternate directions successively, and a worm free to move axially on said last-mentioned shaft with said carriage meshing with said worm gear and turning with said shaft. 10. In an ink agitator for printing presses, a rack mounted adjacent the ink fountain in parallel arrangement therewith, a finger carrier slidably mounted on said rack, a transverse shaft journaled in said carrier, a gear fixed on said shaft and meshing with said rack, a worm gear fixed on said shaft, a shaft journaled adjacent said rack in parallel arrangement therewith and movable axially to a limited extent, a worm free to move axially on said last-mentioned shaft with said carrier meshing with said worm gear and turning 55 said shaft, a pair of continuously-driven bevel gears rotating on said last-mentioned shaft in opposite directions and having clutch teeth, a clutch member fixed on said last-mentioned shaft between said bevel gears and spring-held in clutch with either of said bevel gears, and resilient means adjustably secured on said last-mentioned shaft co-acting with said carrier in shifting said shaft axially. 11. In an ink agitator for printing presses, a carrier having an agitating finger mounted thereon and moving back and forth adjacent the ink fountain, and means extending from said carrier adapted for receiving an additional finger. 12. In an ink agitator for printing presses, a rack mounted adjacent the ink fountain in parallel arrangement therewith, a finger carrier slidably mounted on said rack and moving back and forth, and an extension from said carrier removably secured thereto having a shoe slidably engaging said rack and adapted to receive finger mounting means. 13. In an ink agitator for printing presses, a finger carrier mounted to move adjacent the ink fountain, a shaft journaled adjacent the fountain, gearing actuating said carrier from the rotation of said shaft, a flexible drive shaft operatively connected with said first-mentioned shaft, a bearing mounted to be releasably locked in a raised and lowered positions alternatively and journailling one end of said drive shaft, and gearing between 100 said drive shaft and the printing bed drive operatively connecting said drive shaft to said bed drive when said bearing is in its lowered position and disconnecting said drive shaft from said bed drive when said bearing 105 is in its raised position. Signed at the city of Toronto, this 2nd day of February, 1929.

WILLIAM LINDSAY.
